UNITED STATES PATENT OFFICE.

FRANK THOMPSON, OF CHICAGO, ILLINOIS, ASSIGNOR OF TWO-THIRDS TO THOMAS A. FRASER AND OTTO W. MEYSENBURG, OF SAME PLACE.

DESIGN FOR A BODY-BOLSTER FOR RAILWAY-CARS.

SPECIFICATION forming part of Design No. 27,351, dated July 18, 1897.

Application filed June 3, 1897. Serial No. 639,345. Term of patent 14 years.

To all whom it may concern:

Be it known that I, FRANK THOMPSON, a citizen of the United States, residing at Chicago, in the county of Cook and State of Illinois, 5 have invented a certain new and original Design for a Body-Bolster for Railway-Cars, of which the following is a specification, reference being had to the accompanying drawings, in which—

10 Figure 1 is a side elevation of my newly-designed body-bolster for railway-cars. Fig. 2 is a bottom view of the same. Fig. 3 is a sectional view taken on the line $y-y$ of Fig. 1.

As shown in the drawings, the leading or 15 material feature of my design consists in the upper plate A of the body-bolster, a straight piece of material, and the lower plate B, so bent that at its center a it is parallel with the

upper plate A, and from both sides of which central portion a it is inclined sufficiently to 20 bring its ends in contact with the ends of the upper plate A.

Between the two plates A and B are two webs C of a shape corresponding to the shape of the space between said plates, each web C, 25 as shown clearly in Fig. 3, being set back a short distance from the edges of said plates.

Having described my invention, what I claim is—

The design for a body-bolster for railway- 30 cars, substantially as herein shown and described.

FRANK THOMPSON.
